UNITED STATES PATENT OFFICE.

EDWARD N. PORTER, OF BURLINGTON, VERMONT.

CORNER OR PLATE ATTACHMENT FOR EXTENSION WINDOW-SCREENS.

SPECIFICATION forming part of Letters Patent No. 337,433, dated March 9, 1886.

Application filed May 12, 1885. Serial No. 165,234. (No model.)

To all whom it may concern:

Be it known that I, EDWARD N. PORTER, a citizen of the United States, residing at Burlington, in the county of Chittenden and State 5 of Vermont, have invented certain new and useful Improvements in Corner or Plate Attachments for Extension Window-Screens, of which the following is a specification, reference being had therein to the accompanying 10 drawings.

My invention relates to an improvement in window-screens; and it consists in, first, the combination of the two frames of an extensible screen with a corner-plate secured to one side 15 of one of the frames at its corner, and which is provided with an angular projection which extends over a portion of the other frame and catches in a groove therein; second, a metallic corner brace or plate which is fastened 20 to the inner face of one of the horizontal or sliding bars of one of the screen-frames, on which is a shoulder upon which is formed a projection, the free end of which projection enters and freely moves in a groove in the 25 interior face corresponding to the bar of the other screen-frame, as will be more fully described hereinafter.

The improved construction is simple, cheap, strong, and easy and reliable in operation.

In the drawings, in which similar letters 30 indicate like parts, Figure 1 is a plan view of the device in combination with a metallic corner-brace. Fig. 2 is an end view of the same. Fig. 3 is a perspective view of the extension-screen without the netting. Fig. 4 is a cross-section with the projection shown 35 on the opposite face of the plate in dotted lines. Fig. 5 is a plan view of the projection attached to a plate designed for the lower bar 40 of the frame. Fig. 6 is a similar view of the plate, taken from its opposite side.

A A' and B B' represent the upper and lower bars of the two screen-frames, which extend horizontally. C is an angular projection or hook rigidly attached to a corner-plate, D, or to a bar-plate at the shoulder b, its open or free end d being designed to move or slide in the groove or recess c, cut in the interior faces of the horizontal or sliding bars 50 of the screen-frames.

For the purpose of strength and cheapness I prefer to have the projection cast upon the outer face of a corner-bracket, D, or the bar-plate E, as shown in Figs. 1 and 5. The plate is designed to be firmly attached to the rear 55 face of the interior corners of the frames or to the horizontal bars, as preferred, by means of screws through the holes f f, the opening or free end d of the projection C extending in the direction of the groove in which it is intended to slide, or upward in the plates attached to the top bar (see Figs. 1 and 2) and downward in the plates attached to the bottom bar. (See Figs. 4 and 5.)

To render the fastenings of the plates more 60 firm and the plates more easy to adjust in place, I prefer to project lugs g g from their inner faces, which are designed to press against the interior faces of the bars to which the plates are fastened. Thus constructed, the set 70 of projections attached to each bar are adapted to slide in the groove of the adjacent bar, so that when the two frames are thus combined for the purposes for which they are made they cannot be separated laterally, except by 75 splitting off the entire thickness of the wood between the groove and the projections—a result impossible to occur without the destruction of the frame, inasmuch as the groove is cut in the center or nearer the exterior face of 80 the bar. At the same time the limited width of the projections and character of the material of which they are constructed occasions much less friction in the sliding of the frames than if they extended the entire length 85 of the bar and were composed of wood, which is liable to be affected by heat and dampness.

As the devices are independent of and readily adapted to any screen, the frame-bars can 90 be made of as simple and cheap a character as is desired, care only being taken to provide the grooves e for the projections C in the sliding bars.

What I claim, and desire to secure by Letters Patent, is—

1. The combination of the frames A B of 95 an extensible screen with a corner-plate which is secured to one side of one of the frames at its corner, and which is provided with an angular projection, C, which extends over a 100

portion of the other frame and catches in a groove, *e*, substantially as shown.

2. The projection *C*, having its shoulder *b* firmly attached to or cast upon a metallic corner-brace or to a bar-plate, which is so fastened to the inner face of one of the horizontal or sliding bars of one screen-frame that its free end *d* may enter and freely move in a groove in the interior face of the corresponding bar of the other screen-frame, for the pur-

pose of combining the frames together and enabling them to easily slide upon each other, substantially as described.

In testimony whereof I affix my signature in presence of two witnesses.

EDWARD N. PORTER.

Witnesses:

CHARLES E. ALLEN,
WILL J. MURPHY.
